UNITED STATES PATENT OFFICE.

JOAH BROGDEN, OF MELROSE PARK, PENNSYLVANIA, ASSIGNOR TO DAVID LUPTON'S SONS COMPANY, OF PHILADELPHIA, PENNSYLVANIA, A CORPORATION OF PENNSYLVANIA.

WORKTABLE.

Application filed December 28, 1926. Serial No. 157,443.

REISSUED

This invention relates to work tables of a type more particularly useful to workers customarily known in the knitting industry as "loopers" skilled in transferring knitted fabrics, for example, stocking legs produced on one type of knitting machine, loop for loop to point bars to enable transfer of the work to flat knitting machines for completion of the stocking feet in integral continuation.

The present invention is directed toward provision of a work table especially suitable for the purposes mentioned, capable of economic manufacture from sheet metal; which is extremely compact; strong and sturdy, yet light in weight; absolutely sanitary and vermin-proof; which is equipped with adjuncts and appurtenances necessary or convenient to the operatives; and which provides space for disposal of waste thread ravellings, as well as storage for tools and accessories used by the textile artisans.

How the foregoing desiderata may be readily attained in practice will be manifest from the detailed description hereinafter of the typical embodiment of my invention illustrated in the accompanying drawing which illustrates in perspective a work table incorporating the present improvements.

The table top herein comprehensively designated 1 is fashioned from a rectangular blank of sheet metal with downward bent edges 2—2 that are joined at the corners by welding or in any other convenient manner. By virtue of such construction it will be seen that the table top is well stiffened and strengthened, and on the whole rendered more sturdy.

The supporting sub-structure comprises four leg posts 3, 3 which are fashioned to an angular cross section from comparatively thin metal with their upper ends fitted within and secured to the flange corners of the table top 1. At the lower end of the legs 3 the metal is bent laterally, thereby to provide foot flanges 4 which are perforated as shown in the illustration to take screws or other fastening means when the table is to be secured in place. At a slight elevation from the floor, the legs 3 are joined at opposite sides and the back of the structure, by cross bars 5 also preferably of angular cross section, the opposite bars of the group being in turn joined somewhat inward of the front of the table (that side appearing at the left

of the illustration) by a lateral connecting bar 6 that serves as a foot rest for the operative.

Upstanding from the table top 1 adjacent to one side edge are a pair of spaced brackets 7, 7 which jointly constitute a magazine rack 60 for blank transfer bars. As shown, the brackets 7 provide sloped complementary ledges 8 to support opposite ends of the point bars in such manner as to render the latter easily removable, one by one, as needed 65 by the operative.

The rear portion of the table top 1 is occupied by a pair of centrally-disposed laterally-recessed parallel rails 9 across which the transfer bars are laid with the work hanging 70 over the rear table edge. In the present instance these racks are formed from sheet metal with up-turned ends 10 to restrain the bars from falling out. At one of the forward corners, the table top 1 is equipped with a 75 fixed or stationary rubbing block 12 which is covered with leather and adapted to be used for scoring the fabrics,—an operation by which the loops in the transfer courses of the fabrics are dilated to facilitate impalement 80 upon the points of the transfer bars.

For convenience in disposing of the waste yarn resultant upon ravelling of the "looper's rounds", the table top 1 is provided with a central aperture 13, for direct communication 85 into a drawer 14 that is slidably supported by suitable guides, not shown. This drawer is likewise fashioned from sheet metal with a rolled grasp bead 15 along its front edge, and a partition 16 that sets apart a compartment 90 in the front which may be used for storage of tools and other accessories necessary to the operative.

The structure is further provided with a work holder in the form of an arm 17, which, 95 in the present instance, is screwed fast to the right hand leg 3 at the front of the table. This holder 17 is useful as a hanger to temporarily support a batch of stocking legs which are to be looped on the transfer bar. 100

It is of course to be understood that the appurtenances on the table top 1 may be arranged otherwise than herein illustrated.

Having thus described my invention, I claim:

1. A looper's work table constructed entirely of sheet metal with a top, an open sub-structure to support it at an elevation with

- provision therebeneath of free leg room for the operative, a magazine rack upstanding from the table top adjacent one side thereof, said rack comprising a pair of brackets with 5 inclined ledges to support the opposite ends of a number of blank transfer bars, a pair of spaced rails at the rear portion of the table adapted to be bridged by looped transfer bars with the mounted work overhanging the 10 rear edge of the table, and a scoring block fixed on the table top useful in dilating the loops of the terminal courses of the fabric to facilitate their transfer to the points of the bars.
- 15 2. A looper's work table constructed entirely of sheet metal with a top, an open sub-structure to support it at an elevation with provision therebeneath of free leg room for the operative, a magazine rack upstanding 20 from the table adjacent one end thereof, said rack comprising brackets with inclined complementary ledges of angular cross-section having stop walls at the lower ends, said rack being adapted to support the terminal ends 25 of a number of blank transfer bars, a pair of spaced rails at the rear portion of the table adapted to be bridged by the looped transfer bars with the mounted work overhanging the rear edge of the table, and a leather-faced 30 scoring block stationarily mounted on the table top useful in dilating the loops of the terminal courses of the fabric to facilitate 35 their transfer to the points of the bars.
3. A looper's work table constructed entirely of sheet metal with a top, an open sub-structure to support it at an elevation with provision therebeneath of free leg room for the operative, a magazine rack upstanding 40 from the table adjacent one end thereof, said rack comprising brackets with inclined complementary ledges of angular cross-section having stop walls at the lower ends, said rack being adapted to support the terminal ends 45 of a number of blank transfer bars, a pair of stepped rails embodying stop walls at the rear portion of the table adapted to be bridged by loop transfer bars with the work overhanging the rear edge of the table, and a leather-faced scoring block fixed on the table top useful in dilating 50 the loops of the terminal courses of the fabric to facilitate their transfer to the points of the bars.
4. A looper's work table constructed entirely of sheet metal with a top having a cen- 55 tral aperture communicating into a drawer 60 for the collection of waste material, said drawer being partitioned to provide a stor- 65 age for the operative's tools, an open sub-structure sustaining the table top at an ele- 70 vation with provision therebeneath of free 75 leg room for the operative, a magazine rack on the table top comprising a pair of brackets with inclined complementary ledges of angular cross-section having stop walls at the lower ends, said rack being adapted to sup- 80 port the terminal ends of blank transfer bars, a pair of stepped rails embodying stop walls 85 at the outer ends mounted on the table top and adapted to be bridged by looped trans- 90 fer bars with the mounted work overhanging the rear edge of the table, and a leather-faced 95 scoring block stationarily mounted on the table top useful in dilating the loops of the terminal courses of the fabric to facilitate 100 their transfer to the points of the bars.
5. A looper's work table constructed entirely of sheet metal with a top having a cen- 105 tral aperture communicating into a drawer for the collection of waste material, said drawer being partitioned to provide a stor- age for the operative's tools, an open sub-structure sustaining the table top at an ele- vation with provision therebeneath of free leg room for the operative, a magazine rack on the table top comprising a pair of brackets with inclined complementary ledges of angular cross-section having stop walls at the lower ends, said rack being adapted to sup- port the terminal ends of blank transfer bars, a pair of stepped rails embodying stop walls at the outer ends mounted on the table top and adapted to be bridged by looped transfer bars with the mounted work overhanging the rear edge of the table, a leather-faced scoring block fixed on the table top useful in dilating the loops of the terminal courses of the fabric to facilitate their transfer to the points of the bars, and a hanger on the table sub-structure to temporarily support a mass of the work being operated upon, said hanger having the form of a bar rigidly secured to—and projecting outward from—one of the corner members of the sub-structure aforesaid at a position below the table top.
- In testimony whereof, I have hereunto signed my name at Philadelphia, Pennsylvania, this 22nd day of December, 1926.
- JOAH BROGDEN.
